UNITED STATES PATENT OFFICE.

ALBERT E. HUDSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

METHOD AND MACHINE FOR INSERTING FASTENERS.

Application filed June 30, 1919. Serial No. 307,721.

This invention relates to the setting of fasteners, such for example as eyelets or gromets, which are set with cooperating washers, and it pertains more particularly to utilizing a continuous strip in which the washers are partially formed, severing the washers in completed form as the strip is fed step-by-step, and setting the completely formed and severed washers in co-operative relation to the eyelets or gromets.

It has been heretofore proposed to feed partially formed washers in the form of a strip, to a fastener setting machine. In the use of such previous machines, however, the severing of the washer from the strip resulted in a washer disfigured by irregularities of contour.

An object of the present invention is to provide improved means for severing the washers from the strip in such manner that the resulting washer may be of any desired form, such as, for example, a true circle. It should be distinctly understood, however, that the invention is in no way limited to the forming or setting of circular washers on eyelets, since the washers may equally well be severed in any other desired form, such, for example as elliptical, either as regards their hole or their contour; and of course they may be set on fasteners other than eyelets or gromets.

In the machine herein shown the strip is advanced to position the endmost washer portion between the setting dies, and it is not until then severed from the strip. The severing, moreover, is done by a tool that cuts on opposite sides of, and which may conveniently surround and embrace, one of the fastener setting dies so as to co-operate with the periphery of the latter to cut the washer from the strip, and to trim off from the washer any waste stock which may have been left by the preceding cut.

A feature of the invention consists in a punch-and-die couple to prepare the washer, and a fastener-setting couple of which one member is fixed and is one member of the punch-and-die couple.

Another feature consists in an organization in which a single connecting rod furnishes the operative motion for the punch-and-die couple and also furnishes the motion to feed the strip intermittently to the punch-and-die couple.

Still another feature consists in a detachable unit comprising a supporting bracket, a magazine carried thereby for the strip to be operated upon, and mechanism carried by the bracket for feeding the strip to the instrumentalities that operate upon the strip.

In the utilization of the invention, the two fastener parts, such for example as an eyelet and a washer portion of a washer-strip formed of alternate washer and waste portions, are positioned in concentric registration with each other ready for assembling. The registered washer portion is then severed from the waste or other part to which it was attached, providing, according to the illustrated exemplification, a perfectly formed washer; and thereupon the two fastener parts are assembled and set, as by clinching the eyelet against the washer.

These and other features of the invention will be understood and appreciated from the following description of a preferred exemplification thereof, in which the invention is disclosed, for purposes of illustration, as being embodied in a machine of the general type shown in United States Patent No. 1,191,926, granted July 18, 1916, on an application of Colby, but it is to be understood that this invention is not limited in its scope to use in connection with this type of machine, but on the contrary, in its broader aspects, may be employed in connection with machines and mechanism of widely varying kinds.

Referring to the drawings, Fig. 1 is an elevation showing the general arrangement of a machine constructed in accordance with my invention;

Figs. 2, 3 and 4 are fragmentary views showing various positions of the fastener-setting and washer-feeding mechanism corresponding to different successive phases in the cycle of operation of the machine;

Fig. 5 is a front elevation of the washer-shearing means;

Fig. 6 is a section on the line 6—6 of Fig. 4 showing the fastener-setting dies and the washer-shearing means;

Fig. 7 is a section on the line 7—7 of Fig. 3, and

Fig. 8 shows a portion of a washer-strip as supplied to the machine.

In the drawings 10 indicates the main frame of the machine in which the lower

setting die 11 is carried up and down by plunger 8, and in which the upper setting die or clenching tool 13 is fixed in a boss 14 of the frame 10, although the clenching tool is 5 adjustable up and down and is sustained by a screw-abutment 12 and a retaining screw 9.

The lower die is operated by mechanism that includes a crank 16, connecting rod 15, toggle-couple 20, and lever 21. The fulcrum 10 stud of the latter is indicated at 22, and the front end of the lever embraces a roll 23 carried by the plunger of the lower setting die. The operating crank 16 is carried, in the present instance, by an eccentric 18, and 15 the latter is fixed on a shaft 19. Although the drawings show no clutch mechanism for controlling the rotation of the shaft 19 it is to be understood that any suitable one-revolution clutch will be used, since the machine 20 shown is provided with no work feeding mechanism.

Eyelets are fed to the lower die through the raceway 24 which is reciprocated by any usual or convenient mechanism. In the 25 drawings this reciprocating mechanism is indicated in dotted lines and is of the type shown by the above referred to Patent No. 1,191,926, and consists, in general, of a bell-crank lever 25 mounted on fulcrum stud 26 and pivotally connected at its upper end to the raceway. The other arm of this bell-crank lever has an interior cam surface 27 co-operating with a roll on the end of the lever 21 so that as lever 21 is oscillated the bell-crank lever 25 will be rocked back and forth so as to reciprocate the raceway 24 in 35 proper timed relation to the die 11. The upper end of the raceway may be supported in any appropriate manner to permit the 40 necessary movement thereof, and eyelets may be fed thereto in any desired way.

The periphery of clenching tool 13 constitutes the punch of a punch-and-die couple, and is surrounded by a plate 29 having an upstanding collar portion 30 (Fig. 6) and having a 45 circular aperture 31 (Fig. 7). The punch has a circular shearing edge 32 which operates with this aperture 31 to cut a washer from a washer-strip which is fed thereto by mechanism presently to be described. The collar portion 30 is partly cut away as shown in Fig. 7 to admit the washer-strip, and the remaining portions 33, 34 serve as abutments to register the leading washer portion relatively to the shearing means. The die of the punch-and-die couple is supported by a pair of rods 35 passing through suitable openings in a guiding plate 36 rigidly held at the top of extension 14 of the main frame, 50 the clenching tool 13 also serving to guide the die member. The latter receives operating motion from the eccentric 18 and its surrounding strap 37 to which is rigidly connected the rod 38 pivoted at its other end to bell-crank lever 39 mounted on a stud 40

supported by a depending portion 41 of the bracket 42. To the other end of bell-crank lever 39 is pivotally connected at 43 a collar 44 having lugs 45 to which the guide rods 35 are attached. 70

Also supported by the bracket 42 through a shaft 46 suitably journaled thereon is a magazine 47 illustrated in the form of a reel having a groove 48 therein, in which is carried a coil consisting of a long washer-strip 75 of the form shown in Fig. 8. From magazine 47 the strip passes through a stationary guide 49, mounted as by means of a stud or bolt 65 on the depending arm 41 of bracket 42, and from this guide the washer-strip 80 passes over and across the hole 31 in the plate 29 so that its leading extremity will enter the opening 28 in collar 30 and there be supported by plate 29, as indicated in Fig. 7. The abutments 33 and 34 then engage the 85 leading washer portion so as to register the hole in the latter relatively to the pilot 17 formed in the center of the tool 13, and also to register the partially formed rim of the washer portion relatively to the punch-and-die couple. 90

Means is provided for feeding forward a washer-strip step-by-step, and this will now be described. Attached to the eccentric strap 37 is a stud 53 engaged in a slot 54 of a bell-crank lever 55 pivoted at 56 to a depending portion 57 of bracket 42. To the other arm of this bell-crank lever is attached one end of a curved link 58 adjustably connected at its other end as shown at 59 to a pin 60. As illustrated this adjustable fastening consists of a pair of nuts 61, 62 engaging with a thread on pin 60 so that the point of connection between link 58 and pin 60 may be adjusted as desired. Pin 60 is attached 105 through a universal connection 63 to a curved lever 64 (see Figs. 1 and 2) pivoted at 65 to the end of depending portion 41 of bracket 42. Pivoted to the lower end of lever 64 is 110 a pawl 67 normally held in engagement with the forward edge of a hole in the washer-strip by means of a spring 66. It will thus be seen that rotation of the eccentric 18 will give an oscillating motion to bell-crank lever 55 which transmits this oscillating motion 115 through link 58 to lever 64 so that pawl 67 is given a backward and forward feeding movement. It will be noted that the free end of this pawl is suitably shaped to feed the washer-strip forward while moving in one direction and to slide over it while moving in the other direction. 120

It may be noted here that the machine is 125 enabled to handle strips of variously sized washers by means of the adjustment provided by nuts 61 and 62. By adjusting these nuts, the position of lever 64 and consequently of pawl 67 may be adjusted. When handling small fasteners, the distance between two holes in the washer strip will 130

quently be less than the length of movement of the pawl. To overcome this, the pawl may be so adjusted that it rides up over the upper surface of guide 49 during the last 5 part of its rearward and the first part of its forward movement. During this part of its movement the pawl will be idle, but on passing off the guide it will enter a hole and feed the strip forward. Since the total 10 movement of the pawl is constant, and the idle portion can be varied or eliminated altogether, it follows that the effective movement may be varied to suit the different sizes of fasteners.

15 As all the moving parts of the machine are driven from a single rotating part, namely the eccentric 18, the timed relations of the various movements are necessarily unvarying, except, of course, in so far as they 20 are purposely varied through adjustment by the operator before starting the machine.

25 It is believed that the mode of operation of the machine will be clear from the above description, however, for purposes of convenience it may be recapitulated as follows:

The forward movement of the feeding pawl 65 occurs during the latter half of the downward movement and during the first 30 half of the upward movement of the inserting tool 11, during which period the die plate 29 is depressed relatively to the tool 13 so as to enable the washer-strip to clear the pilot portion 17. The raceway occupies the position shown by Fig. 2 during the first stages of upward movement of the tool 35 11 but is retracted to the position shown by Fig. 3 after the tool has risen far enough to occupy the leading eyelet in accordance with the usual practice. After the tool 11 has taken an eyelet as shown in Fig. 3 the previously punched work is placed upon the eyelet as also shown by Fig. 3, the washer-strip having, by this time, been fed nearly if not quite to its most advanced position for 40 the operation about to be performed. When the hole in the leading washer portion of the strip is in registration with the pilot portion 17 the leading washer portion is registered by the abutments 33 and 34 and is supported by the two waste portions attached to its margin, the waste portion forming the leading end of the strip then resting on the plate 29 between the abutments 33 and 34 as represented in Fig. 7. As the inserting tool 11 45 rises with the eyelet and the article of work engaging the latter the die plate 29 also rises and shears the registered washer portion from both waste portions adjacent thereto. The severed washer portion is then 50 temporarily supported by friction due to the lateral pressure of the die plate against its edge although the upward movement of the washer portion is arrested by the tool 13 before the die plate reaches its highest position. So long as the severed washer remains 55 in the hole 31 of the die plate it is maintained positively against lateral displacement from concentric registration with the eyelet with which it is about to be assembled. During the latter stages of upward movement 60 of the tool 11 the eyelet is introduced through the hole in the washer and is turned over and clenched against the latter as shown by Fig. 6. The return movement of the feeding pawl 65 begins about the moment 65 when the parts are in the positions shown by Fig. 3 so that it will be in position to start its next forward movement when the die plate 29 has descended far enough to enable the leading end of the strip to clear the pilot 70 portion 17.

It will be noted that as shown in Fig. 8 the washer portions are initially connected by short straight webs or waste portions 70, but as the washer portions are registered successively with the punch and die couple the surplus metal or waste portions are trimmed off so that a truly circular washer results. While these portions 70 are spoken of here and in the claims as waste portions, it is to 80 be understood that they are waste only in the sense that they form no part of the completed fastener.

It may be noted also that, in the embodiment illustrated, the strip feeding and washer shearing means are supported on a detachable bracket, which may be fastened as a unit to and bodily removed from the frame of the machine.

Having described my invention, what I 100 claim as new and desire to secure by Letters Patent of the United States is:

1. The combination with fastener-setting mechanism including a fixed clenching tool, of means arranged to feed a washer-strip having a series of washer portions so as to place a washer portion between the clenching tool and the field to be occupied by an article of work, and means constructed and arranged to trim said washer portion at 110 diametrically opposite points and sever it from the strip.

2. The combination with fastener-setting mechanism including a fixed clenching tool, of means arranged to feed a washer-strip 115 into registration therewith, a severing die formed and arranged to surround said tool, and a punch arranged to cooperate with said die to sever a portion of the strip from the latter in registration with the clenching tool 120 to provide a washer.

3. A machine for setting fasteners having, in combination, a fastener setting die, and means having cutting portions on opposite sides of said die and reciprocating relatively thereto for severing a washer from a strip.

4. A machine for inserting fasteners having, in combination, a fastener setting die portions of the opposite sides of the periphery of which form one of the members of 125 130

a shear, and means movable relatively to the fastener setting die to form the other member of the shear.

5. A machine for setting fasteners having, in combination, a fastener setting die, means for feeding a washer strip to the die, and means surrounding the die and reciprocating with respect thereto for severing the end washer from the strip.

10 6. A machine for setting fasteners having, in combination, a fastener setting die the periphery of which forms one of the members of a shear, and a co-operating shear member surrounding the fastener setting die and reciprocable with respect thereto, said last named member being provided with a slot in order that the end of a washer strip may pass therethrough so that the end washer may be severed by the shear and the fastener clenched against the washer.

15 7. A machine for setting fasteners, comprising a fixed tool having a fastener-clenching portion and a punching edge, movable means arranged to cooperate with said edge so as to form a washer from a blank, and means arranged to cooperate with said tool to insert a fastener element through the washer and clench it against the latter.

20 8. A machine for setting fasteners having, in combination, a fastener setting die, means for feeding a washer strip to the die, and means surrounding the die and reciprocating with respect thereto for severing the end washer from the strip, and guiding it to the setting point.

25 9. A machine for setting fasteners having, in combination, a pair of co-operating dies, means for reciprocating one of the dies, means for feeding fasteners to one of the dies, means for feeding the end of a washer strip to the other die, a member co-operating with the last named die and forming therewith a cutting tool, mechanism to reciprocate said member to sever the end portion from the strip, a single drive shaft for the machine, and connections from the drive shaft to the fastener setting means, to the die reciprocating means, to the washer setting means, and to the cutting member, 30 to operate the same in timed relation to feed a fastener to one die and a washer portion to the other, to cut the washer portion from the strip, and to clench the fastener against the washer.

35 10. A machine for setting fasteners having, in combination, a pair of co-operating fastener setting dies, means for feeding fasteners to one of the dies, means for reciprocating one of the dies, the periphery of one of the dies forming one of the members of a shear, a co-operating shear member surrounding said periphery, means for reciprocating said surrounding shear member with respect to the die which it surrounds, and means for feeding the end of a washer strip

to the shear member whereby the end washer portion may be cut from the strip by the shears and the fastener clenched against the washer by the dies.

11. A fastener-setting machine comprising 70 mechanism for setting a fastener, an eccentric, mechanism operable by said eccentric to cut a washer from a washer-strip in position to receive said fastener during its setting operation, and mechanism operable 75 by said eccentric to feed said washer-strip step by step so as to present successive washer portions thereof to said cutting mechanism as aforesaid.

12. A machine for setting fasteners, comprising a punch-and-die couple for forming a washer, and a fastener-clenching couple of which one member is fixed and is a component of the first said couple.

13. A fastener-setting machine comprising 80 mechanism including a crank and connecting rod for operating upon a fastener, and mechanism including said crank and connecting rod for positioning the fastener, said mechanisms being so organized that one 90 of them is operated by longitudinal motion of said connecting rod and the other by lateral motion thereof.

14. A fastener-setting machine comprising 95 mechanism including a crank and connecting rod for feeding a washer-strip step by step, and mechanism including said crank and connecting rod for severing a portion of such strip to form an individual washer, said mechanisms being organized so that one 100 of them is operated by longitudinal motion of said connecting rod and the other by lateral motion thereof.

15. A machine comprising fastener-setting 105 mechanism, and mechanism for supplying washers thereto comprising means for severing a partly formed washer-portion from a washer-strip having a series of such portions, means for feeding the strip so as to place said portions successively in registration with the severing means, and means arranged to engage a previously formed edge of the leading washer-portion of the strip so as to arrest the feeding of that portion when it is in registration with the severing means.

16. In a machine of the character described, means for severing a partly formed washer-portion from a washer-strip having a series of such portions, means arranged to engage a previously formed edge of the leading washer-portion other than the leading edge of the strip so as to register said portion relatively to the severing means, and means arranged to support a portion of the strip in advance of the registered washer-portion.

17. A machine of the character described comprising fastener-inserting mechanism, means arranged to feed a washer strip into the path of insertion of a fastener supported 130

by said mechanism, an abutment arranged to engage the leading end of said strip to register the leading washer portion thereof relatively to said path, and means arranged to sever the leading washer portion so registered.

18. A machine for setting fasteners having a bracket mounted thereon, a magazine for holding a washer strip supported on the bracket, and means also supported on the bracket for feeding the end of the strip to the fastener setting mechanism.

19. A machine for setting fasteners having a bracket mounted thereon, a magazine for holding a washer strip supported on the bracket, means also supported on the bracket for feeding the end of the strip to the fastener setting mechanism, and means for severing the end washer portion from the strip.

20. A machine for setting fasteners having a bracket mounted thereon, a magazine for holding a washer strip supported on the bracket, means also supported on the bracket for feeding the end of the strip to the fastener setting mechanism, means for severing the end washer portion from the strip, and means for clenching the fastener against the washer.

21. A machine for setting fasteners having a bracket mounted thereon, a magazine for holding a washer strip supported by the bracket, step-by-step operated means also supported by the bracket for feeding the end of the strip to the fastening setting mechanism, means for severing a washer portion from the strip, and means for clenching the fastener against the washer.

22. A fastener-inserting machine comprising a crank and connecting-rod, means operable by said connecting-rod to operate repeatedly upon a fastener-strip, and means operable by said connecting-rod to feed said fastener-strip intermittently.

23. A machine comprising a crank and connecting-rod, means operable by said connecting-rod to feed a strip step by step, and other means operable by said connecting-rod to operate upon the strip between feeding steps.

24. A fastener-setting machine comprising a punch and a movable die arranged to shear a washer portion from a strip, said punch having a fastener-clenching surface, and means arranged to cooperate with said surface to set a fastener in the washer.

25. A fastener-setting machine comprising a fixed punch having a fastener-clenching surface, a movable die arranged to cooperate with said punch, and a movable fastener-setting tool arranged to cooperate with said clenching surface.

26. A fastener-setting machine comprising a punch and a die arranged permanently in telescopic relation, said die having a passageway extending transversely to receive a

washer element, and means arranged to set a fastener in said washer element while the latter is in said die.

27. A fastener-setting machine comprising a washer-forming couple and a gromet-clenching couple of which one member is a component of each of said couples and of which two members are arranged to remain in telescopic relation.

28. A fastener-inserting machine comprising a fixed tool having a fastener-clenching surface and a cutting edge, means arranged to cooperate with said tool to cut a washer element, and means arranged to cooperate with said tool to insert a fastener through such washer element and clench the fastener so inserted.

29. In a fastener-inserting machine, the combination with fastener-inserting mechanism, of a fixed punch and a movable die arranged to sever a washer from a strip in the path of a fastener about to be inserted by said mechanism.

30. In a fastener-inserting machine, the combination with a movable fastener-inserting tool, of a washer-serving die arranged to move ahead of said tool in the direction of inserting movement, a punch arranged to cooperate with said die to sever a washer from a strip, and mechanism for operating said tool and said die.

31. A fastener-inserting machine comprising, in combination, a punch-and-die couple and a fastener-inserting couple arranged in coaxial relation, the die member of the first said couple being open at one side between the members of said fastener-inserting couple to receive a washer strip, means at the opposite side of said die member to register the washer strip relatively to said fastener-inserting couple by engagement with its leading edge, means arranged to feed the washer strip to and against said registering means, and mechanism for operating said punch-and-die couple to sever a washer from the strip.

32. A fastener-inserting machine comprising, in combination, cooperative fastener-inserting tools, means arranged to feed a washer strip endwise between said tools, an abutment arranged to engage the leading edge of the strip to register the end portion relatively to said tools, and means arranged to produce an individual washer by severing the end portion of said strip as registered by said abutment.

33. A fastener-inserting machine comprising, in combination, a punch and die arranged to sever the end portion of a strip to produce a washer, means arranged to insert a fastener through the severed washer in line with said punch and die, said die having an opening in one side to receive the washer strip, means arranged to feed the strip endwise through said opening, and

an abutment at the opposite side of said die to register relatively to said fastener-inserting means the strip by engaging its leading edge.

5 34. In a fastener-inserting machine, the combination with fastener-inserting mechanism, of means arranged to feed a strip of partially formed washers to register the leading washer portion of the strip relatively to said fastener-inserting mechanism, and means arranged to sever the leading portion of the strip from the rest of the strip and to sever surplus stock from the margin of said leading portion.

15 35. A fastener-inserting machine comprising, in combination, a punch and die for severing successive end portions from a strip to produce washers, means for relatively moving said punch and die to effect

20 their operation, an abutment arranged to engage the leading end of said strip to register successive washer portions thereof

relatively to said punch and die, means arranged to feed said strip to place the leading end thereof against said abutment, and 25 mechanism arranged to apply the washers so registered by inserting fasteners through them in register with said punch and die.

36. The method of assembling a fastener and a washer which consists in feeding a strip having the peripheries of a series washer portions formed on its longitudinal edges and having a fastener-receiving hole in each of said portions, registering the leading washer portion in a predetermined fastener-receiving position by engaging the previously formed periphery thereof, severing the leading washer portion from said strip while it is registered as aforesaid, and inserting a fastener through the hole in the severed 40 washer portion.

In testimony whereof I have signed my name to this specification.

ALBERT E. HUDSON.

CERTIFICATE OF CORRECTION.

Patent No. 1,615,276.

Granted January 25, 1927, to

ALBERT E. HUDSON.

It is hereby certified that error appears in the printed specification of the above numbered patent requiring correction as follows: Page 5, line 91, claim 30, for the compound word "washer-serving" read "washer-severing"; page 6, line 31, claim 36, after the word "series" insert the word "of"; and that the said Letters Patent should be read with these corrections therein that the same may conform to the record of the case in the Patent Office.

Signed and sealed this 30th day of August, A. D. 1927.

Seal.

M. J. Moore,
Acting Commissioner of Patents.
